JUDSON PRICE, OF POPLAR BLUFF, MISSOURI.

WASTE-PIPE-CLEANING MEANS.

1,215,190.

Specification of Letters Patent. Patented Feb. 6, 1917.

Original application filed May 18, 1916, Serial No. 98,326. Divided and this application filed June 20, 1916. Serial No. 104,788.

To all whom it may concern:

Be it known that I, JUDSON PRICE, residing at Poplar Bluff, in the county of Butler and State of Missouri, have invented a new and Improved Waste-Pipe-Cleaning Means, of which the following is a specification.

This application, except so far as relates to certain minor details of construction, is a divisional part of my copending application, Serial No. 98,326, filed May 18, 1916, for sewer cleaning means and my said present application embodies an improved means for flushing the waste pipes for sinks, wash bowls, bath tubs, and the like and it primarily has for its purpose to provide a waste pipe cleaning or flushing means of a simple and inexpensive character, that can be readily applied to the sink, wash bowl or bath tub, in such manner that the water flow from the bath faucet or the sink tap may be used for flushing the waste pipe.

Another object of my present invention, is to provide in a flushing device for kitchen sinks, bath tubs and the like an improved means for effecting a fluid tight seal of the flushing nozzle or member that is projected into the waste duct in the sink, bowl or tub.

With other objects in view that will hereinafter appear, my present invention consists in the peculiar construction and novel arrangement of the parts to be fully explained, specifically pointed out in the appended claims and illustrated in the accompanying drawing, in which:

Figure 1 is a perspective view of my improved waste pipe flushing means, the same being shown as applied for use in a wash-bowl.

Fig. 2 is a front elevation of the said means, the sink being shown in section to better illustrate the manner in which the flushing water is ejected into the waste pipe.

Fig. 3 is a detail vertical section of the adjustable plug device for making a fluid tight connection of the ejecting nozzle in the waste outlet, and

Fig. 4 is a horizontal section thereof on the line 4-4 on Fig. 3.

In the drawing I have shown my invention as especially adapted for flushing the outlet or waste pipe of wash bowls, kitchen sinks, bath tubs and the like, and in the present showing of my said invention, 1 designates a flushing pipe, one end of which

is externally threaded to receive a screw cap 20 on a hose connection 2, which, when cleaning a bath tub or sink outlet as shown in Fig. 1, is pendently hung into the sink or tub that is kept filled with water from the supply tap, the lower end of the said hose 2 being constantly in the water during the operation of cleaning or flushing the sink waste pipe, and during such operation, the overflow or vent for the sink is closed by a rubber pad, as shown.

5 designates the usual vent pipe that connects with the waste pipe and discharges over the roof, and 50 is a valve in the said pipe for closing the said pipe to prevent forcing the flushing water up the vent pipe 70 during the operation of cleaning the waste pipe.

In my present invention, that is, when the means broadly disclosed in my copending application, is especially designed for use in sinks, wash bowls and bath tubs, the lower end of the main pipe 1 has a threaded portion 35, that terminates with a smooth portion 35^a, that is internally threaded to receive a flanged nut 36, on which is mounted a rubber plug 37.

38 designates a nut that engages the threaded portion 35 of the pipe 1 and the said nut carries a wedged collar 40 for engaging and spreading the rubber plug 37 to thereby cause the said plug to fit air tight in the basin outlet 39, as is clearly shown in Fig. 2.

14 designates a bracket mounted upon the main pipe 1 and it is formed, at one side, with the cylinder portion of a force pump 15 with which joins a pipe section 16 that is in communication with the main pipe 1 at a point in advance of a gate valve 17, located in the pipe 1.

18 is a pipe section that connects the pipe 16 with the main pipe 1 at a point back of the gate valve 17, as shown.

From the foregoing description taken in connection with the drawing, the complete arrangement, the manner of its use and the advantages of my present invention will be readily understood.

By reason of the peculiar way in which the feed hose is attached to the force pump 105 and the main pipe which forms, as it were, the standard for the pump, the device may be readily mounted within a sink, bowl or

tub in such a manner that the operator can readily hold the appliance steady with one hand as he manipulates the force pump with the other and thereby delivers the water gathered from the bowl, sink or tub, under a force pressure, into the waste pipe.

What I claim is:

1. A waste pipe cleaning means, comprising a nozzle adapted to be inserted into the duct to be flushed, the said nozzle including an externally threaded portion and an internally threaded end, a yieldable plug mounted on the end of the nozzle, a clamp nut that engages the internally threaded end of the nozzle for holding the plug in position, a wedge slidable on the nozzle for spreading the plug when inserted into the duct, whereby to effect a fluid tight closure of the said duct, a nut engaging the said externally threaded portion of the nozzle, the said nut and the wedge being joined whereby the wedge is shifted along the nozzle as

the nut is turned, and means for forcing the fluid through the nozzle into the duct.

2. A waste pipe cleaning means comprising a nozzle member adapted to be inserted into the duct to be flushed, means for sealing the said member in the duct, means for holding the said member in the duct and means for forcing fluid through the nozzle into the duct, said means including a main pipe in connection with the nozzle and with the fluid supply, said means for holding the nozzle member in the duct comprising a rubber plug mounted on the nozzle and a wedge member for expanding the plug freely slidable on the nozzle and a nut adjustably mounted on the said nozzle member with which the wedge member is swivelly connected.

JUDSON PRICE.
